JOSIAH H. NICHOLS AND WILLIAM BOWER, OF BEAVER FALLS, PENNSYLVANIA,
ASSIGNORS TO BEAVER FALLS CUTLERY COMPANY, OF SAME PLACE.

Letters Patent No. 99,104, dated January 25, 1870.

IMPROVEMENT IN TABLE-CUTLERY.

The Schedule referred to in these Letters Patent and making part of the same

To all whom it may concern:

Be it known that we, JOSIAH H. NICHOLS and WILLIAM BOWER, of Beaver Falls, in the county of Beaver, and State of Pennsylvania, have invented a new and useful Improvement in Table-Cutlery; and we do hereby declare the following to be a full, clear, and exact description thereof, reference being had to the accompanying drawing, making a part of this specification, in which—

Figure 1 is a side view of a knife blade, and a sectional view of the handle, illustrative our of invention.

Figure 2 is a side view, and

Figure 3 is an edge view of the knife complete.

Like letters of reference indicate like parts in each.

The nature of our invention consists in the manufacture of knives, or other handled articles of table furniture, with a cast-metal shell handle, covering a filling of wood, or other suitable material.

To enable others skilled in the art to make and use our invention, we will proceed to describe its construction and the manner of operation.

We make the blade *a* by forging, or in other known way, from steel, or other suitable material, and either with or without a bolster, *b*.

On the end of the bolster *b*, or on the end of the blade, if a bolster be not made, we forge a tang, *c*, longer or shorter, as may be desired, but at least long enough that a filling, *d*, of wood, or other suitable material, may be attached thereto, the end of the tang *c* being pressed or forced into the end of the filling, or the two being attached together in other convenient way, and also long enough, that the metal of the shell *e* may be cast on to and around the tang *c*, as shown in fig. 1.

The filling *d* we make of any durable shape, and somewhat less in size than the complete handle is to be.

The tang *c* has a groove, *c'*, or is otherwise roughened or collared, so that the metal cast thereon will form a strong and firm joint therewith.

The knife-blade and the filling *d* are then inserted in a properly-shaped mould, vertically, with the base or outer end of the handle upward, and the shell *e* is cast thereon.

In order to prevent the misshaping of the steel *e* by shrinkage, we use, in casting the shell, a mould, having a large sprue, and thus we find the shrinkage is confined to the metal in the sprue, to such extent that the metal shell *e* is not misshapen thereby.

The shell is then polished, plated, or otherwise finished up in any of the ways known in the art.

We thus make a knife which has, in effect, a solid blade and handle, without a joint or seam for the entrance and injurious action of water.

At the same time, we avoid, what is very objectionable, viz, giving to the handle too great a preponderance of weight. This we secure by the filling of wood, or other suitable material lighter than the metals, usually employed for such uses.

The filling may be protected from the injurious action of the hot metal thereon, in casting, by being charred, if of wood, or by being coated with any suitable material or mixture, which is not combustible at the temperature to which it may be raised before the solidification of the shell.

The shell may be made of any metal or metallic compound, or alloy, suitable for such purposes.

If a cast, instead of a forged, bolster be desired, the tang *c* may be made on the end of the blade, and in a mould having a cavity of the proper shape, the shell and bolster may be cast together.

The cavity in which the shell is cast may also have any desired configuration or design made in its face, so as to give the knife-handle, when complete, any desired style of ornamentation.

But if the bolster be cast as just indicated, we usually forge, at the base-end of the blade *a*, a raised rim, *o*, of steel, which protects the soft metal of the handle.

We do not limit ourselves to the mode described, of anchoring the filling *d* in the mould, by attaching it to the tang *c*, but include in our mode of operation any known way of anchoring cores in casting; nor do we limit our invention to a shell cast on to a filling, since the shell may be cast separately, slipped over a suitable filling, and attached to the tang, bolster, or blade by spinning, grooving, or by casting a ferrule on to both at the point of junction, and such mode of manufacture we include in our invention. We also apply it to making not only knives, but also forks, nut-pickers, and other handled articles of table furniture.

What we claim as our invention, and desire to secure by Letters Patent, is—

1. In the manufacture of handled articles of table furniture, a cast-metal shell, combined in handles of table cutlery, with a filling, *d*, substantially as and for the purposes set forth.

2. The filling *d*, in combination with a tang, *c*, and shell *e*, substantially as described.

In testimony whereof, we, the said JOSIAH H. NICHOLS and WILLIAM BOWER, have hereunto set our hands.

JOSIAH H. NICHOLS.
WM. BOWER.
